(57) **CLAIM**

We claim the ornamental design for an oil pan plug with drain valve for vehicle, as shown and described.

DESCRIPTION

FIG. 1 is a perspective view of an oil pan plug with drain valve for vehicle showing our new design;

FIG. 2 is a front elevational view thereof;

FIG. 3 is an elevational view of all sides wherein a lever and slot thereof are not visible;

FIG. 4 is another side elevational view wherein the lever and slot thereof are visible;

FIG. 5 is a top plan view thereof;

FIG. 6 is a bottom plan view thereof; and,

FIG. 7 is a perspective view showing the oil pan plug with drain valve for vehicle in use; the broken lines depict environmental structure for illustrative purposes only and form no part of the claimed design.
